CIRCUIT BREAKER

Winthrop M. Leeds, Wilkinsburg, and Benjamin P. Baker, Turtle Creek, Pa., assignors to Westinghouse Electric & Manufacturing Company, East Pittsburgh, Pa., a corporation of Pennsylvania

Application May 29, 1936, Serial No. 82,493

17 Claims. (Cl. 200—145)

This invention relates to circuit breakers and more particularly to arc extinguishing devices therefor. In the copending applications of W. M. Leeds, Serial No. 697,647, filed November 11, 5 1933, now Patent No. 2,102,326 issued December 14, 1937, and H. J. Lingal and R. C. Dickinson, Serial No. 743,697, filed September 12, 1934, now Patent No. 2,112,033 issued March 22, 1938, both assigned to the assignee of this application, arc 10 extinguishing devices are disclosed which comprise a plurality of insulating plates arranged in stacks and having narrow aligned slots therein so as to provide a narrow chamber or passage of considerable length in which an arc may be drawn longitudinally thereof by the separation of 15 suitable contact members. The arc thus drawn is moved laterally in the slot-like passage and acts upon a material such as oil or other suitable arc quenching media positioned along the walls 20 of the passage to produce a gas which is intermixed with the arc stream to such an extent that the arc stream is deionized and the arc extinguished. Arc movement in each of the above 25 applications is obtained by a magnetic field set up by coil or coils inserted in the arc circuit when the arc is caused to transfer from the main contacts to arc horns which are connected in parallel with the main contacts through the field coils. Transfer 30 of the arc from the main contacts to the arc horns is accomplished by drawing the moving contact member closely adjacent the arc receiving tips of the horns and then moving it a distance beyond the horns so that the main contact separation exceeds that of the arc horns. Inasmuch 35 as the resistance to arc flow across the horns is less than that between the main contacts, transfer of the arc from the main contacts to the horns takes place. We have found, however, 40 that an arrangement for arc movement, as above described, is not reliable over as wide a range of current values as is desirable for some applications. Particularly during the interruption of currents of low value as may be experienced at 45 light or normal line loads, difficulty might be experienced in obtaining effective transfer of the arc on to the arc horns.

It is, therefore, an object of our invention to improve upon prior art arc transfer means and provide means for moving an arc in arc extinguishing devices which is uniformly effective over a wide range of current values. The advent of high-voltage high-speed circuit breakers has also complicated the problem of obtaining reliable arc movement from the main contacts to the arcing 55 horns. The present day requirement for circuit

breakers capable of interrupting high voltages in very short periods of time has led to the production of a design embodying a plurality of breaks considerably in excess of the simple double break construction used in the past. Inasmuch 5 as the voltage appearing across each break of a multiple break interrupter is much less than that across the breaks of a double break structure, considerably less individual gap separation is required. Thus, since the time required to attain 10 the total gap separation varies inversely with the number of breaks, any number of breaks in excess of two will greatly diminish the time required for electrode separation. However, the use of a large 15 number of breaks in series necessitates the multiplication of the arc extinguishing structures and, therefore, complicates the arc moving means. The requirement for more rapid arc extinguishment complicates the arc moving problem still further in that it calls for a more rapid arc movement within the individual arc extinguishing units than has been heretofore practiced.

A further object of our invention, therefore, is to provide an arc extinguishing structure in which the arc moving means are highly efficient and 25 capable of moving the arc at such velocities necessary to meet the requirements of high speed arc extinguishment.

A still further object of our invention is to provide an arrangement of the arc moving coils and 30 the connections thereof for a multiple break arc extinguisher wherein efficient high speed arc movement may be obtained with a minimum number of parts.

A more specific object of our invention is to 35 provide a circuit interrupter in which the main contact members, in addition to their current carrying function when the breaker is closed, also function to establish the arc within the arc extinguishing structure, and in which movement 40 of the arc for the arc extinguishing operation is accomplished by two separate and distinct electromagnetic means successively brought into operation but which have a common effective field of operation.

Other objects and advantages will appear more 45 fully in the following description taken in connection with the accompanying drawings, in which:

Figure 1 is a side elevation of a breaker structure embodying our invention, showing the breaker tank partially in cross section to reveal the arc extinguishing assemblages therefor;

Fig. 2 is a longitudinal sectional view taken 50 through the upper portion of one of the arc ex-

tinguishing assemblages showing the arc moving coils of the uppermost arc extinguishing unit and the coil connections to the next adjacent arc extinguishing unit;

5 Fig. 3 is a fragmentary sectional view of the lowermost arc extinguishing unit, showing the arc moving coils used therein;

Fig. 4 is a perspective view of one of the arc moving coils;

10 Fig. 5 is a partial sectional view taken along line V—V of Fig. 4;

Fig. 6 is a cross sectional view showing the arc passage of an arc extinguishing unit as taken along line VI—VI of Fig. 2;

15 Fig. 7 is a fragmentary developed sectional view of the arc passage; and

Fig. 8 is a circuit diagram of the coil connections of one of the arc assemblages of the breaker of our invention.

20 Referring to the drawings, the reference numeral 10 designates an enclosure or tank provided with two insulating bushings 12, mounted upon the upper wall of the tank 18 and extending interiorly thereof. Each of the bushings 12

25 encloses a metallic lead-in conductor 13, the lower ends of which are adapted to support an arc extinguishing assemblage generally indicated at 15. The two arc extinguishing assemblages 15 are electrically joined by a bridging bar 17 having re-

30 leasable engagement with spring-pressed contacts 19 in circuit with the arc extinguishing assemblage. The bridging member 17 is adapted to be moved into and out of engagement with the contacts 19 by means of a lift rod 21 which is actuated

35 by a suitable mechanism, not shown.

Each of the arc extinguishing assemblages 15 includes a plurality of, in this instance five, arc extinguishing units 23. Each of the units 23 comprises a stack of, in this instance fifteen, circular insulating plates. The stack is formed of plates 25 and 27 alternately placed. The plates 27 are relatively thin and have a curved slot 29 therein, as shown in Fig. 6 for defining the walls of an arc passage. The plates 25 which have 45 considerably greater thickness than the plates 27 are provided with indentures or recesses 31 adjacent the slot 29 so as to form pockets for retaining an additional quantity of arc extinguishing fluid within the slot-like passage.

50 The ends of the stack of plates 25 and 27 are provided with an end plate 33 also of insulating material, each of which carry an arc horn 35 having an arcuate configuration which enables it to extend into the slot 29. Adjacent each insulating end plate 33 is secured a metallic end plate 37 preferably of magnetic material. The entire arc extinguishing assemblage including plates 25, 27, 33 and 37 are adapted to be held together in clamping engagement by means of tie rods 39 preferably of insulating material passing through suitable apertures in the respective plates. The general stack structure of each of the arc extinguishing units 23 is similar and the entire arc extinguishing assemblage 15 is adapted to be assembled upon suitable tie rods not shown, and maintained in proper spaced relation with respect to each other.

55 The uppermost unit 23 of each assemblage 15 has secured thereto a contact foot 41 which, in 70 turn, has threaded engagement with the lower end of its respective lead-in terminal 13 and thereby provides a support for the entire arc extinguishing assemblage. Each of the arc extinguishing units 23 is provided with a pair of contacts, the fixed one of which, indicated at 43,

extends through a suitable aperture in the upper end plate 33 downwardly into the slot or arc passage 29 and a movable contact 45 which extends through a suitable guide member 47 extending through both the lower end plates 33 and 37, the movable contact 45 is adapted to be brought into and out of engagement with the fixed contact 43 by a suitable straight line linkage mechanism generally indicated at 49 which, in turn, is coupled to a common actuating rod 51 by means of a coupling pin 53. The actuating rod 51 is adapted to pass centrally through suitable apertures formed in the stack of plates comprising each of the units 23. The upper end of the operating rod 51 is provided with a follower 55 adapted for reciprocating movement in a cylindrical guide member 57 mounted upon the upper plate 37 of the uppermost unit 23. Secured integrally to the follower 55 is a guide rod 59 about which is placed an accelerating spring 61 which, in turn, is interposed between the end of the cylindrical guide member 57 and the upper end of the follower 55.

55 The lower end of the operating rod 51, as more clearly shown in Fig. 3, is provided with the re- 25 leasable contact member 19 previously referred to which makes both electrical and mechanical connection with the bridging bar 17. Thus when the lift rod 21 is released pursuant to certain conditions when it is desirable to open the breaker 30 contacts, the accelerating spring 61 will forcefully drive the operating rod 51 downwardly which, through its connection with the respective straight line operating linkages 49, will actuate each of the contacts 45 of the respective arc 35 extinguishing units 23 to the open position.

It will thus be seen as the contact 45 in each 40 unit 23 of the two arc assemblages 15 separate simultaneously, an arc will be drawn between each of the contacts 43 and 45. The ends of the arc horns 35 positioned adjacent the contacts 43 and 45 are provided with arc receiving tips 38 and 38, as more clearly shown in Fig. 7. It will be noted that the opposed arc receiving tips 38 and 38 provide diverging arc terminal surfaces for the ends 45 of the arc so that during the initial movement thereof the arc will be progressively lengthened thereby aiding in its extinguishment. Now, in order to obtain effective movement of the arc from the contacts 43 and 45 on to the arc horns 50 55 35, disposed respectively in the upper and lower end of the arc passage 29, two separate and distinct electromagnetic means are employed. The first means comprises what may be termed a series coil 65 positioned in an annular recess 67 provided in the upper metallic end plate 37 of each arc extinguishing unit 23. One end of the coil 65 is directly connected with the fixed contact 43 as clearly shown in Figs. 2, 4 and 5. In fact, the coil 65 also provides the necessary mechanical support for the fixed contact 43. The other end of the coil 65 is connected by means of a screw 69 to a conductor strip 71 which, in turn, is connected by means of a bridging bar 73 to the contact foot 41. The turns of the coil 65 are insulated from each other and from the walls of the annular recess 67 by suitable insulation, as shown. It will thus be seen that current flowing from the incoming terminal 13 through the contact foot 41, bridging bar 73, the conductor 71, coil 65 and contacts 43 and 45 will produce a radial magnetic field across the arcuate slot-like passage 29. This field is augmented and intensified at the upper end of the slot by virtue of the 75

magnetic material comprising the upper end plate 37 in which the coil 65 is embedded.

It therefore follows that as soon as the contacts 43 and 45 separate, an arc drawn therebetween will be acted upon by this radial magnetic field produced by the coil 65 to move at least the upper end of the arc into engagement with the upper arc receiving horn 35. Since the current carrying capacity of the series coil 65 must be equivalent to that of the contacts 43 and 45, the required cross section limits in practice the number of turns to considerably fewer than are necessary to move the arc at a speed which will produce the most effective arc extinguishing action. Therefore, additional means for moving the arc are required which, however, will be brought into play only during the arc extinguishing process. These means are provided by a second coil 75 also positioned in the annular recess 67 in the upper end plate 37 and a similar coil located in a similar annular recess 71 positioned in the lower end plate 37. The two annularly shaped coils 75 positioned in the end plates 37 are preferably of edge-wound construction, as shown, and have a considerably larger number of turns than the series type coil 65 previously described.

In order to simplify the description, the coils 75 will hereinafter be referred to as shunt coils by virtue of the fact that they are connected, as will appear, in parallel with the contacts 43 and 45, while the coil 65 will be referred to as a series coil since it is connected directly in series with the contacts 43 and 45. The upper coil 75 has one end thereof connected by a lead 78 to the connector strip 11 which in turn makes contact between the contact foot 41 and one end of the series coil 65. The other end of the upper coil 75 is connected to the upper arc horn 35. It, therefore, follows that as soon as the upper end of the arc drawn between the contacts 43 and 45 is shifted by virtue of the magnetic field produced by the coil 65 on to the upper arc horn 35 that the upper coil 75 will be inserted in the arc circuit, thus current flowing through the coil 75 will create a strong radial magnetic field across the upper end of the passage 29 to further the movement of the arc along the upper horn 35.

The foregoing description has proceeded on the assumption that the circuit through the moving contact 45 was completed so as to make possible the flow of current through the particular coils above referred to. The particular circuit connections by which the flow of current through the moving contact 45 and through the lower shunt coil 75 of each unit is accomplished will now be described.

A flexible shunt 79 interconnects the lower end of the moving contacts 45 with a bracket 81 which, in turn, makes electrical connection through studs 83 with the lower metallic end plate 37. The lower end plate 37 is connected by a bridging member 85 to the upper end plate 37 of the next adjacent unit 23, the conducting member 87 interconnects the bridging connection 85 through a screw connection 89 to one end of the upper series coil 65 of the next adjacent unit 23. The other end of this last named series coil 65 is connected in the manner previously described in connection with the uppermost unit 23 to the fixed contact 43. The lower end plate 37 of the uppermost unit 23 is also directly connected by means of a screw 91 and a connecting stud 93 to the lower arc horn 35. The lower arc horn 35, in turn, makes connection with one end

of the lower shunt coil 75 while the other end of the lower shunt coil 75 has a lead 85 joining the lead 91 of one end of the upper shunt coil 75 of the next lower unit 23. The other end of the last-named shunt coil 75 is connected to the arc horn 35 of its respective unit in the manner previously described.

The connections for both the series coil 65 and the shunt coils 75 for succeeding units are identical and it is deemed not necessary to describe them in detail. It will be noted, however, that only one series coil 65, positioned in the upper end plate 37, is used in the first four units 23, whereas the lowermost unit 23 has a series coil 65 in both the upper and lower metallic end plates 37. The reason for this particular arrangement will be made apparent subsequently in connection with a consideration of the circuit connections of the coil system of the entire arc extinguishing assemblage.

In order to maintain uniform magnetic circuits for both the upper and lower end plates 37 throughout all of the stacks, the annular recess 71 in the lower end plate 37 of each unit is made identical in dimension with that of the upper recess 67. The space which would be occupied by a series coil 65 in the annular recess 71 adjacent the lower shunt coil 75 is filled in by means of an annular plate 101 preferably made of insulating material.

In the lower end plate 37 of the lowermost unit, a series coil is employed. With particular reference to Fig. 3, the coil designated at 103, in general outline, is similar to the series coil 65. However, since it is used in the lower end plate 37, it must be provided with a suitable aperture to permit the movement of the lowermost contact 45 therethrough. The series coil 103 also differs from the coil 65 in that it does not have a fixed contact secured thereto as does the coil in the latter instance. As shown in Fig. 3, the moving contact 45 is connected as previously described through a flexible shunt 79 to a bracket 105. The bracket 105 is mounted upon the end plate 37 and makes electrical contact therewith, and, in turn, is electrically connected by means of a screw 107 to one end of the series coil 103. The other end of the series coil 103 makes connection through a screw 109 to a bracket 111 which is mounted upon the end plate 37 but insulated therefrom by an insulating plate 113. Electrical connection from the bracket 111 is taken by means of a flexible conductor 115 having one end secured to the bracket 111 by a bolt 117 and having its other end connected to one of the pair of releasable contacts 19 mounted upon the lower end of the operating rod 51. The lower arc horn 35 of the lowermost unit, as shown in Fig. 3, is also connected to one end of the lower shunt coil 75, the other end of the coil 75 being connected by the screw 107 to the lower end plate 37 of that unit.

A more complete understanding of the respective coil connections and the arc extinguishing operation will be had from a consideration of the schematic circuit diagram shown in Fig. 8. With particular reference to the diagram of Fig. 8, the same characters of reference as used in connection with the description of the foregoing figures will be employed. The conductor 18 represents the lead-in terminal 18 heretofore described and is shown making electrical connection with the upper end plate 37. Assuming then that the contacts 43 and 45 are in their closed position, the electrical circuit through the breaker 75

will be from the terminal 13, end plate 37, series coil 65, contact 43, contact 45, shunt connection 79, lower end plate 37, connection 85, which joins the upper end plate 37 of the next adjacent unit 5 23, from whence the circuit is identical through the succeeding units with the exception of the connection from the lower end plate 37 of the lowermost unit 23. This plate is connected to one end of the series coil 103, the other end of 10 which is connected to the movable spring contacts 19. The releasable spring contacts 19 during the closing position of the breaker of one of the arc extinguishing assemblages 15 is adapted to be connected to the releasable spring 15 contacts 19 of the other arc extinguishing assemblage 15 by means of the bridging bar 11. Thus the circuit through to the other arc extinguishing assemblage is identical with that just described and terminates at the other lead in 20 terminal 13 of the breaker.

In the opening operation of the breaker to be subsequently described, reference will only be had to the operation of one of the arc extinguishing units 15, it being, of course, understood that 25 the operation of the other unit 15 which is identical in construction will be similar. Upon the opening of the breaker contacts in response to overload or other predetermined conditions, the lift rod 21 is released from its closed or holding 30 position which permits each of the operating rods 51 to be moved downwardly under the action of the accelerating spring 61 to move each of the movable contacts 45 to the open position. It will be noted that since the series coil 65 and the 35 series coil 103 are connected in series with the contacts 43 and 45 a radical magnetic field will be maintained across the arc passage 29 when the contacts are closed and when an arc is playing therebetween. Thus as soon as the contacts 45 40 separate from the contacts 43, the entire arc will be acted upon by the magnetic field produced by the series coil 65. But since the upper ends of the respective arcs are subjected to a more intense field, these portions will be shifted from the 45 fixed contacts 43 to the receiving tips of each of the upper arc horns 35 prior to movement of the lower portions of the arcs from the contacts 45. Upon the transfer of each of the arcs in the 50 separate extinguishing units 23 to the upper arc horn 35, the arc circuit is now changed and instead of flowing through the fixed contacts 43, the circuit will be from the terminal 13, the upper end plate 37, upper shunt coils 75, upper arc horn 35, movable contact 45, the flexible connector 19, 55 the lower end plate 37, the lower shunt coil 75, connection 95, 97 joining the lower shunt coil of the uppermost unit with the upper shunt coil of the next adjacent unit.

The connections for subsequent units are the 60 same as those above described and need not be repeated. It should be noted that the shifting of the upper end of the arc to the upper arc horn 35 in each of the units 23 causes the upper shunt coil 75 to be inserted in the arc circuit and at the 65 same time causes the series coil 65 of each unit to be disconnected from the circuit. It should also be noted that since the lower shunt coil 75 of the first unit is connected in series by the connections 95, 97, to the upper shunt coil 75 of the 70 next adjacent unit 23 and that the lower shunt coil 75 of the first unit is also connected to the lower end plate 37 which is at the same potential as the moving contact 45 that as soon as the upper end of the arc shifts to the upper arc horn 75 35 that each of the lower shunt coils 75 with the

exception of the lower shunt coil 75 of the lowermost unit 23 will also be inserted in the arc circuit. In other words, with the exception of the lower shunt coil 75 in the lowermost unit 23, both the upper and lower shunt coil 75 become effective 5 upon the mere shifting of the upper ends of each of the arcs to the upper arc horn 35 of each unit.

As soon as the shunt coils 75 become thus energized, a strong radial magnetic field is produced across the respective arc paths having its major 10 concentration at the upper and lower ends of the paths so as to completely transfer the separate arcs drawn between the contacts 43 and 45 on to the arc horns 35. Since the upper and lower shunt coils 75 are simultaneously energized to 15 complete the arc shifting operation from the main contacts 43 and 45 on to the arc horns 35, a series coil in the lower end plate 37 of each unit is not required, with the exception of the lowermost unit 23 where it is desirable to utilize a series coil 20 103, since there is no subsequent adjacent unit having an upper shunt coil 75 to which the lower shunt coil 75 of the last unit may be connected. Thus the series coil 103 in the lowermost unit 23 serves to establish a radial magnetic field at the 25 lower portion of the arc passage 29 of the lowermost unit until the arc is completely transferred from the main contacts 43 and 45 on to the arc horns 35. Once the separate arcs are transferred to their respective arc horns 35, the electrical circuit is as follows. Terminal 13, upper end plate 37, shunt coil 75, upper arc horn 35, through the arc to the lower arc horn 35, lower shunt coil 75, connection 95, 97, the upper shunt coil 75, of the next succeeding unit from whence 35 the connections repeat for each succeeding unit until the lower arc horn 35 of the lowermost unit 23 is reached. From this point on, the connection is through the lower shunt coil 75, series coil 103 and the releasable contact 19.

From the foregoing description, it will be apparent that regardless of the current flowing through the main breaker contacts 43 and 45, in the event that the contacts are separated and the arc extinguishing units 23 are called upon to extinguish the arc, there would always be a radial magnetic field set up by the series coil 65 for initially moving at least one end of the arc on to the upper arc horn 35. Once the arc bridges the upper arc horn 35 and the lower contact 45, complete electrical connection is made for both of the shunt coils 75 of each unit so as to produce a strong joint magnetic field necessary for moving the arc laterally with its ends playing upon the arc horns 35 along the slot 29 with a 55 high velocity. Since the engagement of the arc with the arc quenching fluid contained in the passage 29 produces fairly large quantities of gas which aid in extinguishing the arc, it is necessary to provide means for relieving the pressure 60 within the passage 29. In the application of R. C. Dickinson and W. M. Leeds, Serial No. 82,594, filed May 29, 1936, and assigned to the assignee of this application, an arc extinguishing structure is shown wherein provision is made for venting the arc passage. In the instant application, similar venting means are shown which comprise suitable ports or passages as indicated at 120 which designate a radial portion along one of the plates 25 which is connected by an axial 65 portion 121 extending through the plates 33 and 31, as shown more particularly in Figs. 2 and 3. These passages permit the escape of gas and arc quenching liquid, and thereby prevent the pressure from becoming excessive within the pas- 70 75

sage 28 during the interruption of extremely severe current overloads under which condition fairly large quantities of gas are evolved.

Although we have shown a particular arc extinguishing structure embodying specific means for producing arc movement therein, it is to be understood that the same is for the purpose of illustration and that changes and modifications may be made by those skilled in the art without departing from the spirit and scope of the appended claims.

We claim as our invention:

1. In a circuit interrupter, a pair of separable contact members for establishing an arc, a pair of arc horns of generally annular shape spaced a considerable distance apart for receiving said arc, a coil in series with said contact members for producing a magnetic field to move said arc on to said arc horns, each of said arc horns having a curved arc path thereon between which said arc is adapted to play in one long section, and a second coil in series with said arc horns for producing a radial magnetic field between said arc horns to move the arc laterally along said curved arc paths.

2. In a circuit interrupter, a plurality of pairs of separable contact members for establishing a plurality of serially related arcs, a corresponding plurality of pairs of arc terminals of generally circular conformation between which said respective arcs are subsequently adapted to play, an operating rod movable through the central portion of said arc terminals for actuating said pairs of contact members, a coil in series with each of said pairs of separable contacts for producing a magnetic field to move the said arcs individually on to a corresponding pair of arc terminals, and a second coil disposed about said operating rod and in series with each of said pairs of arc terminals to produce a radial magnetic field for moving each arc along its corresponding arc terminals, said second coils being connected for energization upon the engagement of each arc with at least one of the arc terminals of its respective pair of terminals.

3. In a circuit interrupter, a plurality of pairs of separable contact members for establishing a plurality of serially related arcs, a corresponding plurality of pairs of arc terminals of generally annular shape for receiving the ends of the respective arcs, a coil of annular form concentrically arranged with respect to said arc terminals and in circuit with each pair of separable contacts for setting up radial magnetic fields to move at least one end of each of said arcs individually on to one arc terminal of each of said pairs of terminals, an operating rod movable through the central portions of said arc terminals and said coils for simultaneously actuating said separable contact members, and an auxiliary coil for each pair of arc terminals surrounding said operating rod and arranged to be inserted in its respective arc circuit upon the engagement of one end of the arc with one of its respective arc terminals for setting up radial magnetic fields for moving the arcs along their respective arc terminals.

4. In a circuit interrupter, a plurality of pairs of separable contact members for establishing a plurality of serially related arcs, a corresponding plurality of pairs of arc terminals for receiving the ends of the respective arcs, a coil in circuit with each pair of separable contacts for setting up magnetic fields to move at least one end of each of said arcs individually on to one arc terminal of each of said pairs of terminals, and a

pair of auxiliary coils for each pair of arc terminals arranged to be inserted serially in their respective arc circuits upon the engagement of one end of each arc with its respective arc terminal and also upon the subsequent engagement of the other end of each arc with its respective other arc terminal for setting up magnetic fields for moving the arcs along their respective arc paths.

5. In an arc extinguisher, means of insulating material for defining the walls of a narrow arcuate shaped slot, a pair of separable contact members for drawing an arc within said slot, a pair of arc terminal members disposed in spaced relation within said slot and between which said arc is adapted to play, one end of each arc terminal member being adjacent a contact member, opposed portions of said arc terminal members adjacent said separable contact members having inclined arc paths thereon which diverge in a direction away from said contact members, the remaining opposed portions of said arc terminal members having substantially parallel arc paths thereon, a coil in circuit with said contact members for setting up a magnetic field to move said arc on to said arc terminal members and a second coil connected in circuit with said arc terminal members and adapted to be energized upon the engagement of said arc with at least one of said terminal members for setting up a radial magnetic field across said slot to move said arc laterally therealong in one section with its ends in engagement with said arc paths.

6. In an arc extinguisher, a plurality of plates of insulating material each of which has a curved narrow slot therethrough, said plates being arranged in a stack with their slots in alignment to define the walls of a narrow generally annularly shaped passage, a pair of separable contacts for drawing an arc of considerable length longitudinally of said passage, a pair of arc terminals disposed in spaced relation within said passage for receiving the ends of said arc, a coil responsive to the flow of arc current between said contact members for providing a magnetic field to move at least one end of said arc on to one of said arc terminals, and a second coil responsive at least to the flow of arc current between one of said contact members and one of said arc terminals for producing a radial magnetic field across said passage to move said arc laterally in one long section therealong with its ends in engagement with said arc terminals.

7. In an arc extinguisher, means of insulating material defining the walls of a narrow generally annularly shaped passage, a pair of separable contacts for drawing an arc longitudinally of said passage, an arc terminal in each end of said passage to provide generally circularly shaped paths for the ends of said arc, electromagnetic means initially in circuit with said arc for causing at least one end thereof to be moved from one contact member to one of said arc terminals, a second electromagnetic means in circuit with said arc terminals and adapted to be energized upon the engagement of said end of said arc with the said one of said arc terminals for causing said arc to be moved laterally along said passage with its ends in engagement with said arc terminals, a material along said passage which produces a gas when acted upon by an arc to aid in extinguishing the arc, and vent means enabling the escape of gas from said passage.

8. In a circuit interrupter, means of insulating material for defining a generally annularly shaped narrow slot, means for establishing an arc

- lengthwise of said slot, arc terminals within said slot adjacent said arc establishing means for receiving the ends of said arc, a coil in circuit with said arc establishing means for setting up a magnetic field for moving said arc on to said arc terminals, a second coil in circuit with said arc terminals and adapted to be energized upon engagement of the arc with at least one of said arc terminals for setting up a radial magnetic field 5 across said slot to whirl the arc therealong, said slot having a material therealong which gives off a gas when acted upon by an arc to aid in extinguishing the arc, and vent passages leading from said slot to enable gas to escape therefrom.
- 15 9. In a circuit breaker, a plurality of arc extinguishing units, each of said units comprising means of insulating material for defining a narrow passage, means for simultaneously establishing an arc in each of said passages, said arcs having a series relationship with respect to each other, arc terminals in each of said passages for the ends of the arc established therein, means responsive to the initial arc current for producing a magnetic field at each unit to cause each of 20 said arcs to be moved laterally into engagement with its respective arc terminals, means for each unit made operative by the engagement of at least one end of each of said arcs with one of its respective arc terminals for producing a magnetic field to move each of said arcs along its respective passage, and means along said passage which gives off a gas when acted upon by an arc to aid in extinguishing the arc.
- 30 10. In a circuit breaker, a plurality of arc extinguishing units, each of said units comprising means of insulating material for defining the walls of a narrow arcuate passage, a pair of separable contacts in each of said passages, means connecting said pairs of contacts in series, means 35 for causing the simultaneous separation of said pairs of contacts to establish a series arc in each of said passages, a pair of curved spaced arc terminals in each of said passages for receiving the arc established therein, a coil in circuit with each pair of contacts and positioned adjacent one end of each of said passages for setting up a magnetic field to move at least one end of the arc within said passage into engagement with one of 40 said arc terminals therein, a second coil positioned adjacent the first coil of each of said units connected in circuit with one of said arc terminals and adapted to be energized upon the engagement of said one end of each arc with the said one of said arc terminals for setting up a 45 radial magnetic field across each passage to rotate the arc therein along its respective arc terminals, a material along each passage which gives off a gas when acted upon by an arc to aid in extinguishing the arc, and vent openings, leading from 50 each passage to enable the escape of gas from said passages.
- 55 11. In a circuit breaker, a plurality of arc extinguishing units, each of said units comprising means of insulating material for defining the walls of a slot of generally annular shape, a pair of separable contact members in each slot, means connecting said contact members in series, a common actuating member for simultaneously separating said pairs of contacts to establish a 60 series arc in each of said slots, an arc horn of generally circular shape positioned at each end of each of said slots, a coil situated at one end of each slot and in circuit with the pair of contact terminals therein for setting up a radial magnetic field across each slot to move at least one end of 65

the arc on to one of said arc horns, an auxiliary coil situated adjacent opposed ends of each of said slots and positioned concentrically with respect to said first coil, the auxiliary coil of each unit adjacent the first coil of each unit being connected to one of said arc horns and adapted to be energized upon the transfer of the said end of the arc from one of said separable contacts to the said one of said arc horns for setting up a radial magnetic field across the respective slot, the other 10 auxiliary coil of each unit being connected to the other arc horn and adapted to be energized upon the insertion into the circuit of the first auxiliary coil of a unit next adjacent for setting up a radial magnetic field jointly with said first auxiliary 15 coil of each unit to cause the other end of the arc to transfer to the other arc horn of its respective unit, and for moving the arc along the slot with its ends in contact with the arc horns contained therein, said first-named coil of each unit 20 being disconnected from the arc circuit upon the transfer of one end of each arc to one of the arc horns.

12. In a circuit breaker, means of insulating material for defining the walls of a narrow 25 annularly shaped passage, a pair of contacts, said contacts being engageable for carrying the entire load current of the connected circuit and separable to establish an arc within said passage, arc terminals within said passage between which 30 said arc is adapted to play, a coil in series with said contacts for setting up a radial magnetic field across said passage to move said arc onto said arc terminal means, and a second coil adapted to be inserted into the arc circuit upon 35 the engagement of at least one end of the arc with one of said arc terminals for setting up a radial magnetic field across said passage co-extensive with said first magnetic field for rotating the arc in said passage.

40 13. In a circuit breaker, means of insulating material for defining the walls of a narrow annularly shaped passage, a pair of contacts, said contacts being engageable for carrying the entire load current of the connected circuit and separable to establish an arc within said passage, arc 45 terminals within said passage between which said arc is adapted to play, a coil in series with said contacts for setting up a radial magnetic field across said passage to move said arc onto said arc terminal means, and a second coil adapted to be inserted in the arc circuit upon the engagement of the arc with said arc terminals for setting up a radial magnetic field across said passage co-extensive and jointly operative with said 50 first-named field for moving the arc laterally along said passage.

14. In a circuit interrupter, means of insulating material for defining the walls of a narrow annularly-shaped passage, a main circuit through 60 said interrupter including a pair of contacts engageable for carrying the load current of the connected circuit and separable for establishing an arc within said passage, a branch circuit through said interrupter including a pair of arc 65 terminal members disposed in spaced relation at opposite ends of said passage with one end of each of said members lying adjacent one of said contacts, a coil disposed adjacent each end of said passage and connected serially to the contact next 70 adjacent to establish a radial magnetic field across said passage in response to current flowing through said main circuit for moving said arc onto said arc terminal members, and a second coil concentrically disposed about each of said 75

first-named coils and serially connected to one of said arc terminal members in said branch circuit to establish a radial magnetic field across said passage in response to current flowing through 5 said branch circuit for moving said arc laterally along said arc terminal members, at least one of said first-named coils being common to both the main and the branch circuits.

15. In a multiple break circuit interrupter, a 10 plurality of arc extinguishing structures, a plurality of pairs of serially related separable contacts for establishing an arc in each of said structures, a pair of spaced arc terminal members within each of said structures between which 15 said arcs are adapted to be moved, a plurality of coils within each of said structures, each of said structures having at least one coil connected in series with said separable contacts to establish a field in response to current flow through said 20 contacts for moving the arc onto said terminal members, and two additional coils each of which is connected in series with one of said arc terminal members to establish a magnetic field in response to the current flowing between said terminal 25 members for moving the arc therealong, and means for connecting one of said last-named coils of one structure in series with the other last-named coil of an adjacent structure to thereby complete a branch circuit through said interrupter for carrying the arc current following the separation of said pairs of contacts.

16. In a multiple break circuit interrupter, a 30 plurality of arc extinguishing structures, a plurality of serially related separable contacts for establishing an arc in each of said structures, a pair of spaced arc terminal members within each arc extinguishing structure, a coil adjacent each arc terminal member and connected thereto adapted when energized to produce a magnetic field for moving the arc within each arc ex-

tinguishing structure laterally between its respective arc terminal members, means for moving at least one end of each arc established between said separable contacts onto one arc terminal member of each arc extinguishing structure, and circuit connections between said coils, contacts and arc terminal members so arranged that upon the transfer of said one end of each arc onto the said one arc terminal member of each arc extinguishing structure said coils and arcs will be 10 connected in series circuit relation.

17. In a circuit interrupter, an arc extinguishing structure comprising means of insulating material defining a narrow generally annularly shaped arc passage, a circuit through the interrupter for normally carrying the entire load of the connected circuit comprising an annular coil of low reactance disposed in coaxial relation with and adjacent to one end of said arc passage and a pair of separable contacts within said passage, one of which is directly connected to and supported by said coil, a second circuit through the interrupter comprising an arc terminal member disposed at each end of said arc passage and a coil of relatively higher reactance than said first coil disposed in coaxial relation about said first coil and connected in series with one of said arc terminal members, said first coil maintaining a radial magnetic field across said arc passage during the flow of current through said separable contacts and being effective to move an arc established by the separation of said contacts onto said arc terminal members, said second coil being energized upon the transfer of the arc to at least one of said arc terminal members to provide a radial magnetic field across said arc passage to move the arc laterally therealong.
